WILLIAM HENRY GERHARD, OF AUSTIN, TEXAS.

TOBACCO-PIPE.

1,329,396.

Specification of Letters Patent.

Patented Feb. 3, 1920.

Application filed July 19, 1919. Serial No. 312,011.

To all whom it may concern:

Be it known that I, WILLIAM H. GERHARD, a citizen of the United States, residing at Austin, in the county of Travis and State 5 of Texas, have invented a new and useful Tobacco-Pipe, of which the following is a specification.

This invention relates to tobacco pipes, and the object is to provide a pipe having 10 the outward appearance of an ordinary pipe, and yet embodying advantageous features not found in the latter, said features, to be later enumerated, being incorporated within the improved pipe in a manner to 15 obviate the necessity for unsightly protuberances, or other objectionable or freak formations, which are not desirable to the confirmed smoker.

The principal object is to provide in a pipe 20 of this character means for trapping the nicotine while permitting of free passage of the smoke from the bowl of the pipe to the mouth of the smoker, the said means being carried wholly by the bit of the pipe, which 25 may be readily removed from the said bowl for the purpose of cleansing the smoke passage, or for replenishing absorbent material, which may be utilized within the trap and otherwise cleansing the latter. 30 Further objects are to so arrange the trap as to catch and hold saliva gravitating down the bore of the bit, and to prevent the same from again reaching the mouth of the smoker even though the pipe should be 35 tilted or turned at any angle, and to accomplish these objects with a minimum number of parts which may be assembled for the purpose without the necessity of any nicety of adjustment, or without any possibility of 40 derangement.

A full and complete understanding of the invention may be obtained from a consideration of the following detailed description, taken in connection with the accompanying drawing forming a part of this 45 specification; it being understood that while the latter shows a practical form of the invention, the latter is not confined to strict conformity therewith, but may be changed 50 or modified, so long as such changes or

modifications mark no material departure from the salient features of the invention, as specifically pointed out in the appended claim.

In the drawing, wherein similar reference 55 characters designate corresponding parts throughout the several figures:—

Figure 1 is a longitudinal sectional view through a pipe of a well-known pattern and having the improvements embodied therein. 60

Fig. 2 is a similar view of the bit removed from the stem of the pipe.

Fig. 3 is a sectional view, taken on the line 3—3 of Fig. 1.

Fig. 4 is a detail perspective view of the 65 absorbent material removed from the trap.

Many devices of more or less complicated nature have been incorporated in tobacco pipes for accomplishing the purposes sought herein, and placed upon the market without 70 success for the very reason of their multiplicity of parts, which easily become deranged and require accurate adjustment to secure registration of co-acting ducts, passages, etc., in order to secure the best results, whereas 75 the device of the present invention is so designed as to perform the necessary functions by merely inserting the bit within the stem of the pipe in the usual position, as in ordinary pipes and forcing the same therein to 80 secure the customary frictional engagement for holding the parts together.

While the pipe illustrated in the drawing is of the well-known "Wellington" style, it 85 is to be understood that the invention may be equally as well applied to other styles of pipes and the proper functioning of the parts obtained.

In the drawing 1 indicates the bowl of the pipe having the usual obliquely arranged integral stem 2 provided with a tapering bore 3 longitudinally thereof and extending substantially half the length of the said stem 2. A smoke duct 4 connects the bottom of the tobacco receptacle 5 of the 95 bowl 1 and, inclining upwardly joins the inner end of the bore 3, at the upper side thereof. The usual ferrule 6 surrounds the outer end of the stem 2 for the purpose of strengthening the same,

The removable bit 7, which may be made of any of the materials used for this purpose, is of the common curved type provided with the smoke passage 8, arranged centrally 5 of the said bit, which is provided intermediate its length with the usual annular enlargement 9 adapted, when the bit is in position within the stem 2, to lie adjacent to the ferrule 6 and to provide a gradually 10 tapering shoulder for frictionally engaging the outer end of the bore or socket 3. The inner end of the bit is tapered to a greater degree than the surrounding bore or socket 3, which thus provides between the two 15 parts a space 9^a, gradually increasing in area toward the inner end of the said bore.

This surrounding space 9^a, which has free communication with the bowl of the pipe through the duct 4, acts to cool the smoke 20 somewhat before entering the passageway 8 on its way to the mouth of the smoker. The bit below the annular enlargement has a slightly tangential branch passage 10, which forms a reduced continuation of the smoke 25 passage and terminates in an inlet opening 11, which is thus located well beyond the point where the bit frictionally engages the outer extremity of the bore of the stem 2, and always in a position to communicate 30 with the surrounding space 9^a, for the purpose of receiving the smoke from the bowl, no matter what position the bit 7 may assume with relation to the said bowl. It will be seen that no nicety of adjustment is necessary 35 when placing the bit in the socket of the pipe stem for the purpose of securing the necessary communication with the bowl of the pipe.

At the inner, enlarged end of the bit, there 40 is provided a central longitudinally disposed chamber 12 having its outer end curved, as indicated at 13, to conform to the curvature provided by the enlargement 9 and extending to the inner end of the bit 45 and constituting a trap for nicotin and saliva in a manner to be explained. The smoke passageway 8 communicates with the interior of the trap or chamber 12 by a short duct 14, which connects with the latter at a 50 point where the curvature of the end portion 13 starts, thus forming an inclined entrance opening into the said trap, through which saliva may easily gravitate into the trap, but which will not again enter the 55 smoke passageway 8 no matter if the pipe be turned or tilted. It should be noted that the branch passage 10 is smaller in diameter than the smoke passage 8 and at its junction with the latter is spaced from the duct 14 60 by a partition 15.

At the inner end the bit is reduced and threaded at 15^a for the reception of a screw cap 16, which has an exterior diameter conforming to the bit and which is adapted to

be screwed thereon for closing the inner end 65 of the chamber 12. In practice it has been found advantageous to insert a small roll of blotting paper 17, or some other absorbent material into the trap for the purpose of absorbing the nicotin and saliva which 70 may enter the same, as the said roll may be conveniently placed in position therein and removed from the same, after the bit has been detached from the bowl of the pipe and the cap 16 unscrewed, without soiling 75 the hands of the smoker.

When the bit 7 is inserted in the socket of the pipe stem 2, as illustrated in Fig. 1 of the drawing, and which is the ordinary position in pipes of this character, it will 80 be readily seen that, when the smoker draws upon the passageway through the bit the smoke from the tobacco receptacle 5 will pass through the duct 4 and enter the surrounding space 9^a where it will be partially 85 cooled and thence through the branch 10 into the passageway 8 to the mouth of the smoker without being in any degree deflected. At the same time saliva entering the passageway from the mouth of the 90 smoker will gravitate down the passageway 8, through the short duct 14 and into the trap 12, the said duct 14 being located beneath the smoke inlet 10, so that such saliva is effectually prevented from reaching the 95 smoke duct 4 and thus entering the bowl of the pipe. It will further be seen that by removing the bit from the bowl and then unscrewing the cap and taking out the roll of absorbent material, the chamber or trap 100 may be readily cleansed and a straw or wire readily introduced through the short duct 14 and the passageway 8 to free the same from any particles of tobacco which may have lodged therein, and that the tangential 105 branch 10 constituting the smoke inlet may likewise be freed from such particles by introducing a cleaner through the opening 11 and pushing the same backward through the passageway 8.

From the foregoing it will be seen that an extremely simple construction has been provided whereby the nicotin and saliva is effectively trapped, that the pipe may be easily and quickly cleaned and that the bit 115 may be placed in the stem of the pipe without special care being taken to have the parts function properly.

What is claimed is:—

A tobacco pipe comprising a bowl having 120 a stem provided with a bore communicating with the bowl, a bit having a longitudinal smoke passage terminating short of the inner end of the bit and having a branch passage forming a continuation of the smoke 125 passage and leading to a lateral inlet opening, communicating with the bore, said bit frictionally engaging the bore at a point be-

yond said opening and having at its inner end a longitudinally disposed chamber constituting a trap, said chamber having a curved outer extremity, a short duct connecting the chamber at the beginning of the curved portion with the smoke passage of the bit, and means for closing the inner open end of the bit.

In testimony that I claim the foregoing as my own, I have hereto affixed my signature 10 in the presence of two witnesses.

WILLIAM HENRY GERHARD.
